INVENTOR:

George W. Mosher

BY *Robert Allen*

ATTORNEYS.

UNITED STATES PATENT OFFICE.

GEORGE W. MOSHER, OF NEWPORT, KENTUCKY.

WHIRLIGIG TOY.

1,419,402.

Specification of Letters Patent. Patented June 13, 1922.

Application filed February 21, 1921. Serial No. 446,723.

To all whom it may concern:

Be it known that I, GEORGE W. MOSHER, a citizen of the United States, and a resident of Newport, in the county of Campbell and State of Kentucky, have invented a certain new and useful Whirligig Toy, of which the following is a full, clear, and exact description, reference being had to the drawings forming part of this specification.

10 My invention relates to whirligig toys, of the type which has a drum, with a cord to coil around it, by means of which they are raised and lowered by applying a slight lifting motion to the cord, when the drum has 15 unwound therefrom, said motion being sufficient to cause them to wind the cord up again.

Such toys are popular with children, since they may become quite proficient in dropping the whirling drum and having it return to them.

20 It is the object of my invention to provide a simple, inexpensive toy of this type. It is also my object by the conformation and 25 structure of the drum member to facilitate the operations thereof, and in connection with the drum I provide a means for causing it to rattle during the operations without affecting its perfect balance requisite for 30 even winding and unwinding movement.

I accomplish my objects by that certain construction and arrangement of parts to be hereinafter more specifically pointed out and claimed.

35 In the drawings,

Figure 1 is a perspective view of the device.

Figure 2 is a cross sectional view thereof, on a larger scale than Figure 1. Figure 3 is 40 a detail of the spindle.

I provide a cord 1 having some desirable finger hold 2, by which it is held at its free end, the other end being secured to the drum member.

45 The drum member is formed of a pair of hollow disks mounted upon a spindle. The disks are made up of outer concave plates 3, crimped over inner plates 4, soldering being unnecessary according to my experience.

50 The inner faces of the inner plate 4, as shown at 5, 5, are made flat, so that when assembled on the spindle there is formed an extended space of uniform width, preferably just wide enough to easily contain one strand of the 55 operating cord.

The spindle or pin, is flat and has ends

6, 6, for passing through the disk members, and a widened and perforated central portion 7, which spaces the disks, and provides a point of attachment for the operating cord. 60 The ends 6, 6, have split termini to be bent over for binding the parts together as at 8.

In assembling the disks, small rings 9 or like objects are placed within them, and the spindle is inserted through said objects with 65 the ends of the spindle upset, and the widened central portion serving as a spacer between disks.

The result of this construction is that the rings or what-not will rest against the periphery of the disks, during the spinning operation thereof, and will not accumulate at a certain point in the periphery and throw the device out of balance, since the weight is always borne on the spindles, and 75 a rattling noise imparted to the device which will always be present during operation thereof.

As so constructed the player wraps the cord around the spindle, same fitting easily 80 into the equal width space between the disks, but not jamming therein, and then holding onto the end of the cord, drops the toy. The toy then unwinds from the cord, gaining a rapid revolution, which with a slight upward 85 pull at the moment that the cord is unwound, will cause it to wind up on the cord again and come back to the hand.

I am aware that the toys operating on this principle are not novel, and my invention is directed to the improvements above noted. I may note with regard to the spindle that the spacing portion is rectangular, thereby serving as a tight spacer, even if the disks are forced around on the spindle 95 by rough usage.

Having thus described my invention, what I claim as new and desire to secure by Letters Patent, is:—

1. In a device of the character described, 100 a pair of hollow disks, having their inner faces of a flat conformation, means for securing said disks together, and an operating cord secured at the axial point of said disks, for the purpose described with means 105 mounted loosely on the spindle within the disks to serve as a noise producer.

2. In a device of the character described, 110 a pair of disks, a spindle for mounting said disks, said spindle being widened and slotted intermediate said disks, to serve as a spacer for the disks, and provide a mounting point

for an operating cord, and an operating cord secured in the slot of said spindle, said disks being hollow in form, and means mounted loosely on the spindle within the disks to 5 serve as a noise producer.

3. In a device of the character described, a pair of disks, a spindle for mounting said disks, said spindle being widened and slotted intermediate said disks, to serve as a spacer 10 for the disks, and provide a mounting point

for an operating cord, and an operating cord secured in the slot of said spindle, said disks being formed of concave plates, one of said plates being crimped over the outside of the other, and hollow elements mounted within 15 the disks, and adapted to be threaded onto the spindle when inserting the same, for the purpose described.

GEORGE W. MOSHER.
